ELECTROMAGNETICALLY OPERATED
VACUUM SEALED RELAY

Keith Robert Vale and John Ernest Benson, Sydney, New South Wales, Australia, assignors to Amalgamated Wireless (Australasia) Limited, Sydney, New South Wales, Australia, a company of New South Wales

Application October 19, 1945, Serial No. 623,364
In Australia March 21, 1945

3 Claims. (Cl. 200—87)

1

This invention relates to electromagnetically-operated vacuum-sealed relays primarily adapted for use in making and breaking high voltage contacts, and has particular application in aircraft apparatus operating at low atmospheric pressures.

In the past, various types of vacuum-sealed relays have been suggested for this purpose but all have suffered from one or more disadvantages which limited the scope of usefulness.

A primary disadvantage appears to reside in low efficiency which is due, chiefly, to circumstances arising out of the fact that it is impossible adequately to evacuate the relay when the magnetizing coil is located within the sealed container.

Consequently, it is necessary to locate the magnetizing coil outside the evacuated container which houses the switching contacts and, in conventional relays of the type referred to, the arrangement of the magnetizing coil has been such that the length of the magnetic path is considerably longer than that which could be realized if it were possible to locate the magnetizing coil within the evacuated container.

This results in loss of efficiency because a magnetizing coil of considerably increased proportions and higher operating potentials is required to produce an equivalent magnetizing flux. It will also be obvious that any increase in the physical dimensions of the magnetizing coil produces a consequential increase in weight; an undesirable characteristic particularly where the relay is desired for use in aircraft applications.

The object of the present invention is materially to reduce the size and weight of the magnetizing coil and at the same time greatly to improve the efficiency of an evacuate relay employing a magnetizing coil outside the evacuated container.

The above objective is achieved in accordance with the present invention by locating the core or pole piece of the magnet and the armature of the relay, together with that portion of an evacuated container within which said core and armature are supported, within the core space of an associate magnetizing coil in such a manner that the axis of the armature lies parallel to or coincident with the axis of the core, and by providing means at either or both ends of the core for reducing the length of the magnetic path.

However, for a more complete understanding of the subject invention, practical embodiments thereof will now be described with reference to the accompanying drawings wherein—

Figure 1 is a vertical sectional view of a vacuum

sealed relay in accordance with this invention and adapted for high voltage operation.

Figure 2 is a fragmentary sectional elevation at right angles to Figure 1;

5 Figure 3 is a perspective view of a yoke member; and

Figure 4 is a fragmentary sectional view, equivalent to Figure 1, but illustrating a modified envelope construction for use when one electrode 10 of the relay is to operate at low voltage.

Referring now in particular to Figures 1, 2, and 3 of above mentioned drawings, 10 indicates a glass envelope which is evacuated and sealed off, said envelope being formed with a pair of 15 angularly related electrode supporting arms 12 each incorporating a bubble 13 for increasing the leakage path.

Tungsten electrodes or contacts are indicated by references 14, 15 and 16.

20 The electrode 14 carries a magnetic core or pole assembly comprising a soft iron base member 17 onto which is threaded a pole-piece 18 of similar material, e. g. "Armco" iron, and between member 17 and pole-piece 18 are mounted a soft iron washer 19 and a "micalex" washer 20, the relative dimensions of said washers being such that insulating washer 20 maintains the only slightly smaller iron washer 19 just out of contact with the interior wall surface of envelope 10.

25 30 A soft iron armature 21, formed with oppositely disposed lugs 22, is mounted on the free ends of a pair of tungsten spring legs 23 projecting from washer 19, opposite faces of said armature, near the outer end, being provided with tungsten contacts 15a, 16a.

35 Pole-piece 18 is provided with a radially disposed through aperture 24 to enable evacuation of the screw threaded interior thereof, and near the reduced upper end of said pole-piece there is provided a limiting stop 25, of non-magnetic metal, to prevent armature 21 from touching and "sticking" to the pole-piece under the influence of residual magnetism.

40 The upper end of pole-piece 18 is reduced as shown in Figure 1 to enable armature 21 to lie substantially in the axial plane of said pole-piece.

45 As illustrated by Figure 1, the neck portion of envelope 10 with the above described assembly located therein is mounted within the central bore of a non-magnetic bobbin 26 carrying relay winding 27, the envelope 10 being secured in position within bobbin 26 by means of a wax 28 so that portions of a soft-iron yoke 29, now to be described, are aligned with lugs 22 and washer 19.

50 55 The yoke 29, illustrated in detail in Figure 3,

comprises a reclining U-shaped member having a web 38 and upper and lower flanges 31 and 32 respectively, the upper flange 31 being provided with an opposed pair of ears 33 while the lower flange 32 is formed with a through aperture 34.

In the illustrated example, the yoke 28 is secured to the bobbin 26 by means of bolts 35 passed through flanges 31 and 32.

The ears 33 are formed by twisting the parallelly disposed lugs 36, projecting from flange 31, whereby the so formed ears are adapted to lie closely adjacent the envelope 18 in transverse alignment with the lugs 22 on armature 21.

Similarly, the aperture 34 in flange 32 of yoke 28 is transversely aligned with washer 19 associated with pole-piece 18.

If desired, an insulated terminal board or strip may be mounted on web 38 of yoke 28.

The effective magnetic path in the above-described arrangement may be traced from flange 32, through the wall of aperture 34 to washer 19 and pole-piece 18, across gap to armature 21, from lugs 22 on the latter to ears 33 on flange 32 and finally through the latter and web 38 back to flange 31.

It will therefore be appreciated that the path defined is constituted entirely of iron except for the relatively small gaps 34-18, 18-21 and 22-33.

In the inoperative or non-energized condition, contacts 15, 15a are made but in the operative or energized condition of the relay, the free end of the pole-piece 18 becomes polarized in opposite sense to the adjacent end of armature 21 and the magnetic force pulls said armature across to make contacts 16a, 16.

Since lugs 22 and ears 33 are disposed in planes that are parallel to the path of motion of armature 21, the forces acting on lugs 22 are at right angles to such path and cannot retard free action of armature 21 in either direction along said path. Moreover, the reluctance of the gap (22-33) may be considerably reduced by making the lugs 22 as large as practicable.

From Figures 1 and 2 it will be observed that armature 21 extends beyond the free end of pole-piece 18; this disposition is necessary when it is desired that said armature be attracted to, and not repelled by, pole-piece 18.

Therefore, although the illustrative example described above requires armature 21 to be attracted to the core or pole-piece 18 it will be evident that the physical dimensions of the pole and armature may be related as above indicated to attain a repelling action without departing from the instant invention.

Figure 4 illustrates a modification of the envelope 18 for use when one electrode (e. g. 15) is to operate at a low potential and, in view of the foregoing, no further description of the last mentioned figure is deemed necessary.

Finally, it is to be noted that the subject relays will still operate with a reasonable degree of efficiency in the absence of ears 33 and lugs 22 but then the flux path outside of the iron would be longer with consequential higher reluctance.

What is claimed is:

1. An electromagnetically operated vacuum-sealed relay comprising an evacuated envelope housing a plurality of switching contacts, one of said switching contacts carrying a relay pole-

piece whereof the upper end is reduced to permit location of an armature substantially in an axial plane of said pole-piece, said armature being mounted on a magnetic washer member in contact with the other end of said pole-piece, the others of said contacts being mounted for cooperation with said armature, the portion of said envelope containing said pole-piece and armature being mounted within the core space of an associated magnetizing coil, and a magnetic yoke member of U-formation embracing said coil and having one of its ends located in transverse alignment with, and in closely spaced relation to, a pair of transversely aligned lugs provided one on each longitudinal edge of said armature, the other end of said yoke member being in transverse alignment with, and closely spaced from, said magnetic washer.

2. A relay according to claim 1 and wherein said armature is mounted on said magnetic washer by means of a pair of spring legs extending from said washer.

3. An electromagnetically operated vacuum-sealed relay comprising an evacuated envelope housing a plurality of switching contacts, one of said switching contacts carrying a relay pole piece whereof the upper end is reduced to permit location of an armature substantially in the axial plane of said pole piece, said armature being mounted on a magnetic washer member in contact with the other end of said pole piece, the others of said contacts being mounted for cooperation with said armature, the portion of said envelope containing said pole piece and armature being mounted within the core space of an associated magnetizing coil, and a magnetic yoke member of U-formation embracing said coil and having one of its ends located in transverse alignment with, and in closely spaced relation to a pair of transversely aligned lugs provided one on each longitudinal edge of said armature, the other end of said yoke member being in transverse alignment with and closely spaced from said magnetic washer, said magnetic washer being annularly spaced from the interior surface of said envelope by means of said insulating washer which is slightly larger in diameter than said magnetic washer, said insulating washer being mounted between said magnetic washer and a base member carried by said one electrode.
